OSCILLATING VALVE

Filed Feb. 8, 1932

UNITED STATES PATENT OFFICE

1,974,454

OSCILLATING VALVE

Louis P. Gamache, Inglewood, Calif.

Application February 8, 1932, Serial No. 591,521

2 Claims. (Cl. 123—81)

My invention relates generally to valves and more particularly to the type of oscillating valve set forth in U. S. Letters Patent No. 1,781,901, issued November 18, 1930.

5 The principal objects of my invention are, to generally improve upon and simplify the construction of the valve disclosed in the aforesaid patent, as well as other similar forms of oscillating valves and to provide an oscillating valve 10 and its actuating mechanism that is capable of being readily assembled or taken apart so as to facilitate inspection, adjustments and repairs.

Further objects of my invention are, to provide a relatively simple and efficient bearing for 15 the lower portion of the stem of the valve and which bearing comprises a minimum number of parts that are capable of facile adjustment in order to maintain the valve in proper operative position and further, to construct the valve and 20 its operating mechanism so that it will act positively to control, without leakage, the flow of gaseous fuel into the combustion chamber of an engine and also to control the discharge of products of combustion from the combustion chambers.

With the foregoing and other objects in view, my invention consists in certain novel features 25 of construction and arrangement of parts that will hereinafter be more fully described and 30 claimed and illustrated in the accompanying drawing in which:

Fig. 1 is an elevational view of an internal combustion engine equipped with my improved oscillating valve and its operating means.

35 Fig. 2 is an enlarged vertical section taken on the line 2—2 of Fig. 1.

Fig. 3 is an elevational view of the body of the valve.

Fig. 4 is a horizontal section taken on the line 40 4—4 of Fig. 2.

Fig. 5 is a horizontal section taken on the line 5—5 of Fig. 2.

Fig. 6 is a horizontal section taken on the line 6—6 of Fig. 2.

45 Referring by numerals to the accompanying drawing which illustrates a practical embodiment of my invention, 10 designates the cylinder block of the engine, 11 the combustion chamber therein, 12 the piston that operates within the 50 combustion chamber and 13 a port and throat that communicates with the upper portion of the combustion chamber and which port may be either the inlet or exhaust port.

Projecting laterally from the upper ports of 55 the cylinder block 10, is a valve housing 14 and

rigidly positioned therein is a sleeve 15 provided with diametrically opposite ports 16, one of which communicates with the port and throat 13 and the opening 17 through this sleeve tapers gradually toward its lower end, thereby providing a 60 tapered seat for the oscillating valve.

The upper end of the valve chamber within the sleeve 15, is closed by a removable plate 18, through which is formed a horizontally disposed duct 19 and leading downwardly from said duct 65 and communicating with the upper ends of the valve chambers in the sleeves 15, are ports 20.

Duct 19 is suitably connected to a source of liquid lubricant supply, for instance, a pump that draws liquid lubricant from the sump in 70 the lower portion of the crank case.

A manifold 21 is suitably connected to the outer face of the valve block 14 and communicates with the port 16 opposite the port that 75 communicates with the port 13.

Arranged for oscillatory movement within the tapered valve chamber 17, is a tapered valve 22 provided with a diametrically arranged port 23, the ends of which are adapted to register with the ports 16 during the oscillatory movement of 80 said valve and formed in the top of this valve is a recess 24 that is adapted to receive lubricant from the port 20.

Leading through the wall of the valve, just above the bottom of the recess 24, are diametrically opposite ports 25, and formed in the periphery of the valve body and leading downwardly from the outer ends of these ports are small vertically disposed grooves 26 that terminate adjacent to the lower ends of the valve body. These 85 ports 25 and grooves 26 are located on the surface of the valve body between the ends of port 90 23 and they provide means for conducting liquid lubricant unto the surface of the valve as it oscillates and also unto the surface of the tapered 95 valve seat.

The upper end of a valve stem 27 is detachably secured in any suitable manner, preferably by means of a pin or key 28, to the lower end of valve 22 and the lower portion of this valve stem 100 is journaled in an adjustable bearing that is mounted on the upper portion of the crank case 29.

Formed in the upper portion of the crank case is a threaded opening 30 and formed in the crank 105 case at one side of this opening and in communication therewith, is a notch 31.

The external threaded lower portion of a sleeve 32 is screw-seated in the opening 30 and the upper end of the sleeve terminates in a square or 110

hexagonal body 33 that may be engaged by a wrench or like tool for screwing the sleeve upwardly or downwardly through its threaded seat 30.

5 A lock nut 34 is screw-seated on the threaded portion of sleeve 32 and when tightened against the upper surface of the crank case, this nut securely locks the sleeve in its vertically adjusted position. This lock nut is in the form of a disc 10 provided in its edge with notches 35 for the reception of a spanner wrench or like tool.

The lower portion of the opening through sleeve 32 is enlarged to form a chamber for a ball bearing 36 and the outer race of this bearing bears 15 against the shoulder at the upper end of the chamber in said sleeve and the lower end of this outer race is engaged by a ring nut 37 that is screw-seated in the lower end of the chamber in the lower portion of the sleeve.

20 The upper end of the inner race of the ball bearing bears against a shoulder 38 that is formed on the lower portion of stem 27 and the lower end of said inner race is engaged by the upper end of the hub portion 39 of an arm 40 and which latter is disposed at right angles to the axis of the valve stem or spindle 27.

Hub 39 is detachably connected in any suitable manner, preferably by means of a pin or key 41 to the lower end of stem 27 and depending from 30 the outer end of arm 37 is a pin 42.

The length of arm 40 is such that it will pass 35 upwardly through the notch or opening 31 when the valve and its operating parts are removed for the purpose of inspection, adjustment or repairs.

The hub portion of a lever 43 is pivotally mounted on a pin or post 44 that depends from the upper portion of the crank case adjacent to the opening 30 that is occupied by sleeve 32 and this 40 lever occupies a position immediately beneath and parallel with arm 40.

The free end of lever 43 is provided with a short 45 longitudinally disposed slot 45, through which passes pin 42.

Depending from the intermediate portion of lever 43, is a stud 46, upon which is journaled a roller 47 and this roller occupies the eccentric groove 48 that is formed in a cam 49 and the latter being carried by cam shaft 50. This cam shaft 50 is suitably driven at proper speed from the crank shaft of the engine.

During operation of the engine with which my improved oscillating valve is associated, the roller 47, engaged by groove 48 in cam 49, imparts 55 swinging movement to lever 43 and the engagement of the pin 42 in slot 45 imparts swinging movement to arm 40 and due to the difference in the length of lever 42 and arm 40, the latter will swing through a greater arc than lever 43 and thereby impart the desired oscillatory movement to stem 27 and valve 22.

As the ends of the port 23 in the valve register with the ports 16 in sleeve 15, communication is 65 established between the combustion chamber and the manifold to permit gaseous fuel to enter the combustion chamber or to permit burnt products of combustion to pass from the combustion chamber to the manifold and in proper time relation to the movement of piston 12 the valve will be

oscillated so as to move the ends of port 23 out of registration with ports 16, thereby cutting off the further flow of gaseous fuel or products of combustion through the valve.

During this oscillatory movement of the valve 80 and its stem, the lower portion of said stem operates with minimum friction as a result of the provision of the ball-bearing between the lower portion of said stem and sleeve 32 and during oscillation of the body of the valve, the surface 85 thereof and the surface of the tapered seat 17, is lubricated by liquid lubricant that passes through ports 25 and flows downwardly through the grooves 26.

Sleeve 32 may be screwed upwardly or downwardly in its seat to provide the necessary adjustment for the bearing at the lower end of the valve stem and after such adjustment the sleeve 90 and bearing may be locked by tightening nut 34.

By removing plate 18 and unscrewing sleeve 95 32 from the crank case the valve, its stem and the bearing for the lower portion of said stem may be readily removed for the purpose of inspection or repairs and during such removal the end of arm 40 passes upwardly through notch or 100 opening 31.

Thus it will be seen that I have provided an oscillating valve that is relatively simple in construction, inexpensive of manufacture, capable of being readily assembled or taken apart and which 105 is very effective in performing the functions for which it is intended.

My improved valve is positive and reliable in 110 operation and is capable of being easily and accurately adjusted so as to take up any wear that may occur and consequently preventing leakage of the gaseous fuel or products of combustion that pass through the valve and the sleeve in which it oscillates.

It will be understood that minor changes in the 115 size, form and construction of the various parts of my improved oscillating valve may be made and substituted for those herein shown and described without departing from the spirit of my invention, the scope of which is set forth in the 120 appended claims.

I claim as my invention:

1. In an engine, an oscillating valve, comprising 125 a valve stem, a valve carried by one end of said stem, a sleeve screw-seated in a threaded opening in a fixed part of the engine in which the valve is associated, means for locking said sleeve in differently adjusted positions, an arm carried by the lower portion of said valve stem, there being an opening in the fixed part of the engine to permit the insertion and removal of 130 said arm while positioned on said stem and means for imparting swinging movement to said arm to oscillate said valve carrying stem.

2. In an internal combustion engine, the combination with a valve stem, of a bearing adjustably seated in a fixed part of the engine structure, which bearing receives the lower portion of said valve stem, an arm carried by said stem below said bearing and there being an opening 135 formed in the engine structure adjacent to said bearing for permitting the insertion and removal of said arm while secured to said stem.

LOUIS P. GAMACHE.
